UNITED STATES PATENT OFFICE.

SAMUEL A. SMITH, OF NEWARK, NEW JERSEY.

RECORD-SHEET.

SPECIFICATION forming part of Letters Patent No. 437,256, dated September 30, 1890.

Application filed June 5, 1890. Serial No. 354,366. (No specimens.)

To all whom it may concern:

Be it known that I, SAMUEL A. SMITH, a citizen of the United States, residing at Newark, in the county of Essex and State of New Jersey, have invented certain new and useful Improvements in Record-Sheets; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

The present invention relates to certain improvements in record-sheets, and has for its object to expedite and simplify the finding of names; and the invention is designed to furnish builders and contractors with a record-sheet containing the building contracts or agreements and mechanic-lien claims filed on any day at the county court-house of the State.

The invention is illustrated in the accompanying drawing.

In carrying my invention into effect I employ a sheet *a*, of paper of any convenient size, which is preferably ruled with horizontal lines *b* and vertical lines *c*, forming the rectangular spaces, as shown in the drawing. The top of the sheet is provided with the proper heading, viz: "—— county clerk's office," in which the name of the county can be printed or filled in in writing, and beneath this heading are found the following words: "List of building agreements and mechanics' lien claims, filed ——, 189—."

As illustrated in the drawing, the sheet *a* is divided into four vertical columns, each of which is divided into five rectangular spaces, thus making a total number of twenty such spaces to a sheet. Of course this number of spaces is not essential, and the sheet may contain more or less, which will largely depend upon the average amount of agreements recorded daily at the different court-houses.

As indicated in the drawing, the spaces in the first three vertical spaces or columns contain a record of the different agreements filed on the day indicated at the top of the sheet, while in the last column are recorded the mechanic-lien claims for the same day.

The agreement-spaces contain each the fol-

lowing printed matter, viz: "Owner," "No. of agreement," "Date of agreement," "Date of filing," "Builder," "Location of building," "Constructed of," "Contract for," "Architect," "Remarks," "Amount of contract," "First payment," "Second payment," "Third payment," "Fourth payment," "Fifth payment," "Sixth payment," with the proper spacing behind these words to be filled in, according to the terms of the agreement, by the official at the county clerk's office.

The "Mechanic lien claims" column contains the following printed matter, as follows: "Claimant and," two or three lines for the name and residence of the owner of the building, "Amount of claims," "Location of building," "Date of filing," and "Summons issued." These spaces are written up at the clerk's office after all the agreements, &c., have been received for the day and a copy sent to each builder, mason, or contractor, whereby they are at all times provided with the information of the agreements recorded for the current day, being informed as to all particulars, thus saving the time and trouble of making personal searches at the clerk's office. The record-sheets can be filed away, and every builder or contractor thereby being provided with a complete record of agreements and mechanic-lien claims filed.

Of course it will be understood that I do not restrict myself to the exact arrangement and number of spaces shown in the drawing, the printed forms being arranged approximately as shown; but the horizontal lines *b* and vertical lines *c* can be entirely dispensed with, if desirable.

Having thus described my invention, what I claim is—

1. The herein-described record-sheet, ruled at its top to provide a space containing the permanent headings, "—— county clerk's office," and beneath it "List of building agreements and mechanic lien claims, filed ——," and horizontally ruled by lines *b* into smaller spaces, and also by vertical lines forming vertical columns or spaces over the entire surface of the sheet, all of equal dimensions, each of which contains certain permanent data, substantially as and for the purposes set forth.

2. The herein-described record-sheet, ruled at its top to provide a space containing the

permanent headings, "—— county clerk's office," and beneath it "List of building agreements and mechanic lien claims, filed ——," and horizontally ruled by lines *b* into smaller spaces, and also by vertical lines forming vertical columns or spaces over the entire surface of the sheet, all of equal dimensions, the left-hand vertical columns or spaces containing certain permanent data for entering a list of the building-agreements filed, and the right-hand vertical spaces containing cer-

tain permanent data for entering a list of mechanic's-lien claims, all of said parts being arranged substantially as and for the purposes set forth.

In testimony that I claim the invention set forth above I have hereunto set my hand this 3d day of June, 1890.
